DESIGN FOR A SOAP TRAY OR SIMILAR ARTICLE

Francis E. Reeve, Chicago, Ill.

Application November 10, 1943, Serial No. 111,639

Term of patent 3½ years

To all whom it may concern:

Be it known that I, Francis E. Reeve, a citizen of the United States, residing at Chicago, in the county of Cook and State of Illinois, have invented a new, original, and ornamental Design for a Soap Tray or Similar Article, of which the following is a specification, reference being had to the accompanying drawing, forming a part thereof.

I claim:

The ornamental design for a soap tray or similar article, as shown.

FRANCIS E. REEVE.
